UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed June 3, 1929. Serial No. 368,114.

This invention relates to mining machines and more particularly pertains to coal mining machines of the flexibly fed, continuous cutter type.

An object of this invention is to provide an improved coal mining machine and more particularly an improved mining machine of the flexibly fed, continuous cutter type having improved flexible feeding and guiding means. Another object is to provide improved flexible feeding and guiding means for a mining machine of the aforesaid type wherein a plurality of relatively rotatable feed operating and controlling members are employed which are adapted to draw in and pay out in an improved manner cooperating flexible feeding means whereby the machine may be fed and guided in an improved manner. Yet another object is to provide an improved mining machine feeding mechanism of the multi-drum type having improved driving and controlling mechanism for the drums whereby the latter may be driven at either a fast or a slow speed and selectively in opposite directions at either speed without reversing the machine driving motor. Still another object is to provide an improved multi-drum cable feeding mechanism for a coal mining machine wherein separate driving and controlling means are provided for each drum whereby the drums may be driven either separately or simultaneously at relatively slow speed or at relatively high speed and selectively in either direction at either speed while the machine driving motor runs continuously in the same direction. Another object is to provide in a feeding mechanism of the aforesaid type an improved transmission mechanism including separate reversing mechanisms embodied in the drive for each feeding member and also including a separate fast and slow speed drive for each feeding member. A further object of this invention is to provide in a mining machine of the aforesaid type improved feeding mecha-

nism including a feed drum and a controlling drum and improved driving mechanism for each drum operative to effect drive thereof either in winding direction or unwinding direction separately or simultaneously at a relatively slow cutting speed or at a relatively high machine moving speed, and including means to permit rotation of said drums in unwinding direction under various degrees of frictional resistance, or to permit said drums to revolve freely in unwinding direction. Another object is to provide an improved room and pillar coal mining machine of the "low-vein" type especially adapted to use in mines having narrow or low veins of coal. These and other objects and advantages of this invention will, however, more fully appear in the course of the following description and as more particularly pointed out in the appended claims.

In the accompanying drawings there is shown for purposes of illustration one embodiment which the invention may assume in practice.

In these drawings,

Fig. 1 is a top plan view of the improved mining machine, the cutter bar being partially broken away.

Fig. 2 is a side elevational view of the machine shown in Fig. 1.

Fig. 3 is a horizontal sectional view taken substantially on line 3—3 of Fig. 2.

Fig. 4 is a central, longitudinally extending, vertical sectional view taken substantially on line 4—4 of Figs. 1 and 3.

In this illustrative construction there is shown a mining machine of the flexibly fed, continuous cutter, room and pillar type comprising a low compact frame 1 of generally rectangular shape having a smooth bottom surface 2 adapted to rest upon and slide in any direction over the mine floor. The frame 1 comprises a central motor section 3 supported on a bed section 4 and interposed between the cutter and feed frame sections 5

and 6, these frame sections when united forming a rigid low compact frame on which the various mechanisms of the machine are supported. As shown, the cutter frame section 5 is disposed at the forward end of the machine frame and projecting forwardly from the cutter frame and rigidly secured thereto is a horizontal plane cutter bar 7 supporting on its margin an orbitally movable cutter bit carrying cutter chain 8. Mounted in an improved manner on the feed frame section 6 at the rear end of the machine and disposed on the opposite sides of the machine upon horizontal transversely extending axes are relatively rotatable feed operating and controlling members 9 and 10 and cooperating with said members are flexible feeding elements 11 and 12 respectively, the feed operating and controlling members and their co-operating feeding elements being herein in the form of winding drums cooperating with feed cables or ropes. Housed within the motor frame section 3 is a horizontal motor 13 having its power shaft 14 horizontally disposed and extending longitudinally of the machine frame and driving from its opposite ends respectively the cutting and feeding mechanisms, the motor being of the type adapted to effect drive of the feeding and cutting mechanisms selectively in opposite directions and which herein may be of the reversible electric type.

The cutting mechanism and the driving mechanism therefor are of the same general design as those described in a copending application, Serial No. 312,732, filed October 15, 1928. The cutter driving mechanism generally comprises a bevel pinion 15 suitably rigidly fixed to the forward end of the motor shaft 14 and meshing with a bevel gear 16. This bevel gear drives a spur pinion 17 meshing with a larger spur gear 18 connectible, in a manner clearly described in the copending application mentioned above, in driving relation with the cutter chain 8. As the specific construction of the cutting mechanism does not specifically enter into this invention, further description of the same is thought to be unnecessary.

Now referring to the improved flexible feeding means, it will be noted that mechanism is provided operative to effect rotation of the winding drums 9 and 10 selectively in winding or unwinding direction either separately or simultaneously at a relatively slow cutting speed or at a relatively high machine moving speed without reversing the machine driving motor, and includes means operative to permit the winding drums to revolve in unwinding direction under various degrees of frictional resistance or to revolve freely in unwinding direction. To attain these functions a separate and distinct plural speed reversible driving connection is employed for each drum and includes a fast speed gear

train and a slow speed gear train, each having a separate frictional controlling means for each speed. These improved driving connections comprise a spur pinion 20 suitably rigidly fixed to the rear end of the motor shaft 14 and meshing with a spur gear 21 herein preferably formed integral with a horizontal longitudinally extending shaft 22 having its axis arranged parallel with and in a plane below the motor shaft. This shaft 22 is journaled in ball bearings 23 suitably supported within the feed frame section and has also formed integral therewith a spur pinion 24 meshing with the spur gear 25 secured as by a key 26 to a horizontal shaft 27 having its axis arranged parallel with and in a plane below the shafts 14 and 22. As shown in Fig. 4, this shaft 27 is journaled in ball bearings 28 suitably supported within the feed frame section and has secured thereto as by a key 29 at its rear end a bevel pinion 30. This bevel pinion meshes with a bevel gear 31 secured as by a key 32 to a vertical shaft 33. This shaft 33 is journaled at its upper and lower ends and intermediate its ends in ball bearings 34 suitably supported by the feed frame section. Secured to the shaft 33 is a worm 35 and secured as by a key 36 to the upper end of this shaft is a spur gear 37 meshing with a larger spur gear 38 secured as by a key 39 to a vertical shaft 40 arranged parallel with and in the rear of the shaft 33. This shaft 40 is journaled at its upper and lower ends within the feed frame section in ball bearings 41 and has secured thereto a worm 42. The worm 35 has teeth oppositely inclined from and of less inclination than the teeth on the worm 42 and these worms rotate in opposite directions, the worm 35 being a fast speed worm while the worm 42 is a slow speed worm.

In this instance, meshing with the worm 35 at opposite sides thereof are fast speed worm wheels 43 and 44 connectible by friction disc clutches 45 and 46 to horizontal longitudinally extending shafts 47 and 48 respectively. These shafts are arranged in parallel relation and their axes are disposed in vertical planes spaced equidistantly at each side of the longitudinal center of the machine. These worm wheels 43 and 44 are driven in the same direction and are supported on their respective shafts on ball bearings 49 and 50 respectively supported by the shafts, while these shafts are each journaled in ball bearings 51 and 52 suitably supported within the feed frame section. Meshing with the opposite sides of the slow speed worm 42 and driven by the latter in the same direction are slow speed worm wheels 53 and 54 connectible by friction disc clutches 55 and 56 to the shafts 47 and 48 respectively. As the friction clutches within the worm wheels 43, 44, 53 and 54 are substantially identical in design, the description of one will suffice for

all. Carried by each of the worm wheels is a series of clutch plates 57 interleaved by a corresponding series of clutch plates 58 carried by a clutch member 59 keyed to the shaft. 5 The operating mechanism for the clutches 45 and 55 comprises a shipper yoke 60 pivoted at 61 within the feed frame section and pivotally connected at 62 to a longitudinally extending operating rod 63. This operating 10 rod is threadedly connected at 64 to a nut 65 rotatably mounted within the rear end wall of the machine frame. This nut is formed integral with an operating handle 66. Similar operating mechanism is employed for the 15 friction clutches 46 and 56 and includes an operating handle 67.

Secured to the forward ends of the shafts 47 and 48 respectively are bevel pinions 68 and 69. As illustrated, the bevel pinion 68 meshes with the reverse bevels 70 and 71 journaled on ball bearings 72 supported on a horizontal shaft 73. This shaft 73 extends transversely of the machine and is journaled in ball bearings 74 suitably supported within the 20 feed frame section. The reverse bevels 70 and 71 are selectively connectible by friction disc clutches 75 and 76 respectively to the shaft 73 to effect rotation of the latter selectively in opposite directions. Suitably secured as by a key 77 to the outer end of the 25 shaft 73 is a spur pinion 78 meshing with an internal gear 79 herein formed integral with the feed drum 9.

Again referring to the driving connections 30 for the controlling drum 10, it will be observed that the bevel pinion 69 meshes with reverse bevels 80 and 81 journaled on ball bearings 82 supported by a horizontal shaft 83. This shaft 83 is aligned with the shaft 73 35 and is journaled in ball bearings 84 suitably supported within the feed frame section. The reverse bevels 80 and 81 are selectively connectible to the shaft 82 by friction disc clutches 85 and 86 respectively to effect rotation of the shaft 83 selectively in opposite 40 directions. Secured as by a key 87 to the outer end of the shaft 83 is a spur pinion 88 meshing with an internal gear 89 herein formed integral with the drum 10. As shown 45 in Fig. 3, the drums 9 and 10 are each journaled on the side of the machine frame on a laterally projecting stub shaft 90 formed integral with a plate member 91 secured as by screws 92 to the side of the machine frame. 50 Supported on this stub shaft 90 are ball bearings 93 on which the winding drum is rotatably supported. The winding drum and supporting bearings therefor are held against axial displacement from the stub shaft by 55 means of a screw and washer connection 94 and the complete bearing structure for the drum is arranged within a bore 95 formed within the drum. The operating mechanism for the clutches 75 and 76 within the reverse 60 bevels 70 and 71 comprises a shipper yoke 96

suitably mounted at 97 within the feed frame section. This shipper yoke is pivotally connected at 98 to a longitudinally extending operating rod 99 having a suitable operating handle 100 conveniently located at the rear 70 end of the machine adjacent the control handle 66 for the speed controlling clutches for the drum 9. Similar operating mechanism is employed for controlling the clutches 85 and 86 within the reverse bevels 80 and 81 and 75 includes a pivoted shipper yoke 101, an operating rod 102 and a controlling handle 103 located adjacent the other clutch control handle 67. It will thus be seen that when the proper friction clutches within the worm 80 wheels are applied and upon suitable application of the proper friction clutches within the reverse bevels, the feed and controlling drums 9 and 10 may be rotated selectively in opposite directions at either a relatively high 85 speed or at a relatively low speed.

Means are provided for guiding the cables 11 and 12 during the various operations of the machine and herein comprise guide sheaves 105, 106 disposed on opposite sides 90 of the forward end of the machine frame, each of these guide sheaves being supported by a pivoted swing arm 107 in turn carried by a bracket 108 secured as by a screw 109 to a side of the cutter frame section 5. Arranged 95 at the opposite sides of the rear end of the machine frame are guide sheaves 110 and 111 each mounted on a support 112 secured as by screws 113 to the side of the feed frame section 6. As shown in Figs. 1 and 2, when the machine is cutting from right to left, the cable 11 extends from the top of the feed drum 9 forwardly along the side of the machine and around the front guide sheave 105 laterally from the front end of the machine. 100 The controlling cable 12 extends from the bottom of the controlling drum rearwardly along the side of the machine, around the guide sheave 111 laterally from the rear end 105 of the machine. When the machine is cutting from left to right, the cable 11 is passed around the rear guide sheave 110 while the cable 12 is extended along the side of the machine and around the front guide sheave 110. 110

The operation of the machine will now be described. The machine is propelled about the mine while mounted on its transport truck and when the working place is reached, the machine is unloaded from the truck onto the mine floor in a well known manner. The cable 12 is then extended from the drum 10 forwardly along the side of the machine around the front guide sheave 106 and forwardly from the machine to a suitable anchor or roof jack located adjacent the coal face at the right hand rib. The operator then manipulates the control handle 67, swinging the shipper yoke 60 into a position to apply the friction clutch 46 within the fast speed 115 120 125 130

worm wheel 44 and upon application of the friction clutch 86 within the bevel gear 81 the drum 10 may be rotated at a relatively high machine moving speed in a direction to wind in the cable 12, and as a result the machine is fed bodily over the mine floor to a position adjacent the coal face at the right hand side of the room, the friction clutch 46 thereafter being released. If it is desired, the machine may be moved over the mine bottom at a fast speed by means of the feed drum 9 and cooperating feed cable 11, or under some conditions both the cables 11 and 12 may be used to feed the machine. After the machine is suitably positioned adjacent the coal face, the cable 12 is disconnected from the front guide sheave 106 while still retaining its connection with the jack and the cable 11 is extended from the feed drum 9 forwardly along the side of the machine around the front guide sheave 105 and laterally from the front end of the machine transversely across the coal face to a suitable anchor or rib jack located adjacent the face at the left hand rib. The cutter chain 8 is then connected to the motor and the friction clutch 56 within the slow speed worm wheel 54 is then applied and the clutch 86 is loaded and the drum 10 is rotated at a relatively slow cutting speed in a direction to wind in the cable 12, thereby moving the machine forwardly toward the face to effect the sumping cut, the clutch 56 thereafter being released. As the cutter bar is sumped into the coal, the feed drum 9 is rotated in a direction to maintain the feed cable 11 under tension, thereby guiding the machine as the cutter bar is sumped beneath the coal face. If desired, the feed drum 9 and feed cable 10 may be used to sump the cutter bar beneath the coal or under some conditions both the cables 11 and 12 may be extended to anchors adjacent the coal face and wound in to effect sumping of the cutter bar. After the cutter bar has been sumped beneath the coal face the operator applies the clutch 55 within the slow speed worm wheel 53 and upon application of the clutch 75 within the bevel gear 70 the feed drum 9 may be rotated in a direction to wind in the feed cable 11 and the machine is straightened up and fed transversely across the coal face at a cutting speed. At the same time the clutch 56 within the worm wheel 54 is applied and the controlling drum 10 is rotated in a direction to wind in the controlling cable 12, but due to the opposing forces caused by the pull of the feed cable 11 on the forward end of the machine and the reaction of the cutters against the coal, the controlling cable 12 is pulled off from the drum 10 under the frictional resistance of the friction clutch 56. If it is desired during the transverse cutting operation to angle the cutter bar, the operator may release the controlling drum 10 from its drive,

thereby permitting the drum to rotate freely and as a result the rear end of the machine is swung forwardly due to the pull of the feed cable 11 on the front end of the machine frame. If it is desired to swing the cutter bar forwardly, this may be accomplished by applying the fast speed friction clutch 46 and the friction clutch 86 within the reverse bevel 81, thereby causing the drum 10 to be rotated at a high speed in a direction to wind in the controlling cable 12, thereby swinging the rear end of the machine rearwardly and angling the cutter bar. The cutter bar may be swung forwardly also by the application of the fast speed friction clutch 45 to cause the feed drum 9 to wind in the feed cable 11 at a relatively high speed. It will be evident that by the provision of the reverse bevels 80 and 81 the controlling drum 10 may be rotated in a direction to unwind the controlling cable 12 while the feed drum 9 is rotated in a direction to wind in the feed cable 11 during the transverse cutting operation, the drum 10 paying out the cable 12 at the same rate as the drum 9 winds in the feed cable 11. At the end of the transverse cut, the machine is angled relative to the coal face and the feed cable 11 is disconnected from its jack and the front guide sheave 105 and extended from the feed drum 9 to an anchor or roof jack located at the rear of the machine. The drum 9 is then rotated in a direction to wind in the cable 11 at a relatively slow speed and the cutter bar is withdrawn from the coal. The machine is then hauled over the mine bottom at a relatively high speed by one or the other, or both, of the cables 11 and 12 and loaded onto a transport truck. Other operations of the improved mining machine will be clearly apparent to those skilled in the art. As a result of this invention it will be noted that an improved mining machine is provided having improved feeding mechanism whereby the machine may be fed and guided in an improved manner. It will further be noted that an improved mining machine feeding mechanism is provided of the multi-drum type having improved driving and controlling means for the drums whereby the latter may be rotated selectively in opposite directions without reversing the machine driving motor, either separately or simultaneously, at relatively high speed or at relatively slow speed, may rotate in unwinding direction under various degrees of operator-controlled frictional resistance, or may rotate freely in unwinding direction. It will further be noted that the improved feeding mechanism is of a symmetrical and well balanced design, the driving connections between the motor and each of the drums being identical in construction, thereby enabling a substantial number of the parts to be duplicated with a resultant decrease in the cost of manufacture.

While there is in this application specifically described one embodiment which the invention may assume in practice, it will be understood that this form of the same is shown for purposes of illustration and that the invention may be modified and embodied in various other forms without departing from the spirit or the scope of the appended claims.

What I claim as new and desire to secure by Letters Patent is:

1. In a mining machine, a motor, cutting mechanism driven thereby including an elongated kerf cutter, and feeding means driven by said motor including relatively rotatable feed operating and controlling members each adapted to cooperate with flexible feeding means and mechanism for independently driving said members at either a relatively low speed or a relatively high speed and selectively in opposite directions at either speed while said motor runs continuously in one direction, said driving mechanism including means whereby said members may be driven by said motor simultaneously but with one revolving at a different speed from the other.

2. In a mining machine, a motor, cutting mechanism driven thereby including an elongated kerf cutter, and feeding means driven by said motor including relatively rotatable feed operating and controlling members each adapted to cooperate with flexible feeding means and a plural speed reversible transmission mechanism for each member through which it but not the other member may be driven whereby said members may be independently driven at either a relatively low speed or a relatively high speed and selectively in opposite directions at either speed while said motor runs continuously in one direction.

3. In a mining machine, a motor, cutting mechanism driven thereby including an elongated kerf cutter, and feeding means driven by said motor including relatively rotatable feed operating and controlling members each adapted to cooperate with flexible feeding means and separate plural speed driving connections for each member through which it but not the other member can be driven whereby said members may be driven either separately or simultaneously at a relatively low speed or a relatively high speed and selectively in opposite directions at either speed without reversing said motor.

4. In a mining machine, a motor, cutting mechanism driven thereby including an elongated kerf cutter, and feeding means driven by said motor including relatively rotatable feed operating and controlling members each adapted to cooperate with flexible feeding means and separate plural speed driving connections for each member through which it but not the other member

can be driven whereby said members may be driven either separately or simultaneously at a relatively low speed or a relatively high speed and selectively in opposite directions at either speed without reversing said motor, said driving connections including means whereby said members may rotate in one direction under various degrees of frictional resistance.

5. In a mining machine, a motor, cutting mechanism driven thereby including an elongated kerf cutter, and feeding means driven by said motor including relatively rotatable feed operating and controlling members each adapted to cooperate with flexible feeding means and separate plural speed driving connections for each member through which it but not the other member can be driven whereby said members may be driven either separately or simultaneously at a relatively low speed or a relatively high speed and selectively in opposite directions at either speed without reversing said motor, said driving connections including means whereby said members may rotate in one direction under various degrees of frictional resistance or freely.

6. In a mining machine, a motor, cutting mechanism driven thereby including an elongated kerf cutter, and feeding means driven by said motor including relatively rotatable feed operating and controlling members each adapted to cooperate with flexible feeding means and separate plural speed driving connections for each member through which it but not the other member can be driven whereby said members may be driven either separately or simultaneously at a relatively low speed or a relatively high speed and selectively in a direction to draw in said flexible feeding means at either speed or in a direction to pay out said flexible feeding means at either speed all without reversing said motor, said driving connections including means whereby said members may rotate in a direction to pay out said flexible feeding means under various degrees of frictional resistance.

7. In a mining machine, a motor, cutting mechanism driven thereby including an elongated kerf cutter, and feeding means driven by said motor including relatively rotatable feed operating and controlling members each adapted to cooperate with flexible feeding means and separate plural speed driving connections for each member through which it but not the other member can be driven whereby said members may be driven either separately or simultaneously at a relatively low speed or a relatively high speed and selectively in a direction to draw in said flexible feeding means at either speed or in a direction to pay out said flexible feeding means at either speed all without reversing said motor, said driving connections in-

cluding means whereby said members may rotate in a direction to pay out said flexible feeding means under various degrees of frictional resistance or to rotate freely in a direction to pay out said flexible feeding means.

8. In a mining machine, a motor, cutting mechanism driven thereby including an elongated kerf cutter, and feeding means driven by said motor including relatively rotatable feed operating and controlling members each adapted to cooperate with flexible feeding means and driving connections for said members including a separate reversing mechanism for each member whereby said members may be independently driven selectively in opposite directions and at the same angular speed in either direction while said motor runs continuously in the same direction.

20 9. In a mining machine, a motor, cutting mechanism driven thereby including an elongated kerf cutter, and feeding means driven by said motor including relatively rotatable feed operating and controlling members each adapted to cooperate with flexible feeding means and fast and slow speed driving connections for said members including a separate reversing mechanism for each member whereby said members may be independently driven selectively in opposite directions at either speed while said motor runs continuously in the same direction.

10. In a mining machine, a motor, cutting mechanism driven thereby including an elongated kerf cutter, and feeding means driven by said motor including relatively rotatable feed operating and controlling members each adapted to cooperate with flexible feeding means and driving mechanism for said members including separate reversible gear trains for each member through which it but not the other member may be driven for independently driving said members selectively in opposite directions and at the same angular speed in either direction without reversing said motor.

11. In a mining machine, a motor, cutting mechanism driven thereby including an elongated kerf cutter, and feeding means driven by said motor including relatively rotatable feed operating and controlling members each adapted to cooperate with flexible feeding means and driving mechanism for said members including separate fast and slow speed gear trains for each member through which it but not the other member can be driven for independently driving said members at either a relatively slow speed or at a relatively high speed and selectively in opposite directions at either speed without reversing said motor.

12. In a mining machine, a motor, cutting mechanism driven thereby including an elongated kerf cutter, and feeding means driven by said motor including relatively rotatable

feed operating and controlling members each adapted to cooperate with flexible feeding means and driving mechanism for said members including separate fast and slow speed gear trains for each member through which it but not the other member can be driven for driving said members separately or simultaneously at either a relatively slow speed or at a relatively high speed and a reversing mechanism in the drive between said motor and said gear trains for each member for effecting rotation of said members selectively in opposite directions at either speed without reversing said motor.

13. In a mining machine, a motor, cutting mechanism driven thereby including an elongated kerf cutter, and feeding means driven by said motor including relatively rotatable feed operating and controlling members each adapted to cooperate with flexible feeding means and driving mechanism for said members including separate fast and slow speed gear trains and a reversing mechanism for each member through which it but not the other member can be driven for independently driving said members at either a relatively slow speed of a relatively high speed and selectively in opposite directions at either speed without reversing said motor.

14. In a mining machine, a motor, cutting mechanism driven thereby including an elongated kerf cutter, and feeding means driven by said motor including relatively rotatable feed operating and controlling members each adapted to cooperate with flexible feeding means and driving mechanism for said members including separate fast and slow speed gear trains for each member through which it but not the other member can be driven and having a separate frictional control for each speed for independently driving said members at either a relatively slow speed or a relatively high speed and selectively in opposite directions at either speed without reversing said motor.

15. In a mining machine, a motor, cutting mechanism driven thereby including an elongated kerf cutter, and feeding means driven by said motor including relatively rotatable feed operating and controlling members each adapted to cooperate with flexible feeding means and driving mechanism for said members including separate fast and slow speed frictionally controlled gear trains and a frictionally controlled reversing mechanism for each member through which it but not the other member can be driven for independently driving said members at either a relatively slow speed or a relatively high speed and selectively in opposite directions at either speed without reversing said motor.

16. In a mining machine, a motor, cutting mechanism driven thereby including an elongated kerf cutter, and feeding mechanism driven by said motor including relatively

5 rotatable feed operating and controlling members each adapted to cooperate with flexible feeding means and mechanism for independently driving said members including a separate plural speed transmission mechanism and a reversing mechanism for each member whereby said members may be driven at a plurality of predetermined speeds and selectively in opposite directions at 10 either speed without reversing said motor.

10 17. In a mining machine feeding mechanism, a motor, a rotatable feed member adapted to cooperate directly with flexible feeding means, driving connections between said motor and said member for rotating the latter in either of opposite directions at the same angular speed, and including reversing means, a relatively rotatable controlling member adapted to cooperate directly with 15 flexible controlling means, and a separate and distinct driving connection between said motor and said controlling member.

15 18. In a mining machine feeding mechanism, a motor, a rotatable feed member adapted to cooperate directly with flexible feeding means, driving connections between said motor and feed member for rotating the latter at relatively high speed or at relatively low speed and including reversing means for 20 effecting rotation of said member in either of opposite directions at either speed and without reversing said motor, a relatively rotatable controlling member adapted to cooperate directly with flexible controlling 25 means, and a separate and distinct driving connection between said motor and said controlling member.

20 19. In a mining machine feeding mechanism, relatively rotatable feeding members 40 disposed with their axes parallel to a transverse vertical plane and each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission 45 mechanism including a longitudinally extending shaft, a fast speed gear train, and a slow speed gear train, each gear train including a terminal gear coaxial with said shaft and connectible to drive the same.

45 20. In a mining machine feeding mechanism, relatively rotatable feeding members disposed with their axes parallel to a transverse vertical plane and each adapted to cooperate directly with flexible feeding means, 50 and motor operated devices for driving said members either separately or simultaneously in a direction to draw in their respective flexible feeding means at relatively high speed or at relatively low speed including a separate and distinct plural speed transmission mech- 55

anism for each member, each transmission mechanism including a longitudinally extending shaft, a fast speed gear train, a slow speed gear train, each gear train including a terminal gear coaxial with said shaft, and friction clutches one individual to each terminal gear for connecting said gears in driving relation with said shaft. 70

21. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including alined shafts one connected to each member, and a separate and distinct plural speed transmission mechanism for each shaft, each transmission mechanism including a longitudinally extending shaft, a fast speed gear train, and a slow speed gear train, each gear train including a terminal gear coaxial with said longitudinal shaft and connectible to drive the same. 75 80 85 90

22. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including alined shafts one connected to each member, and a separate and distinct plural speed transmission mechanism for each shaft, each transmission mechanism including a longitudinally extending shaft, a fast speed gear train, a slow speed gear train, each gear train including a terminal gear coaxial with said longitudinal shaft, and friction clutches one individual to each terminal gear for connecting said gears in driving relation with said shaft. 95 100 105

23. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including alined horizontal shafts one connected to each member and a separate and distinct plural speed transmission mechanism for each shaft, each transmission mechanism including a longitudinally extending shaft, a fast speed gear train, and a slow speed gear train, each gear train including a terminal gear coaxial with said longitudinal shaft and connectible to drive the latter. 110 115 120

24. In a mining machine feeding mechanism, relatively rotatable feeding members each adapted to cooperate directly with flex- 125 130

ible feeding means, and motor operated devices for driving said members either separately or simultaneously in a direction to draw in their respective flexible feeding means at relatively high speed or at relatively low speed including alined horizontal transversely extending shafts one connected to each member and a separate and distinct plural speed transmission mechanism for each shaft, each transmission mechanism including a longitudinally extending shaft, a fast speed gear train, and a slow speed gear train, each gear train including a terminal gear coaxial with said longitudinal shaft and connectible to drive the latter.

25. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including alined shafts one connected to each member, a separate and distinct plural speed transmission mechanism for each shaft, each transmission mechanism including a longitudinally extending shaft, a fast speed gear train, a slow speed gear train, each gear train including a terminal gear coaxial with said longitudinal shaft, and a reversing mechanism coaxial with each alined shaft.

26. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including alined shafts one connected to each member, a separate and distinct plural speed transmission mechanism for each shaft, each transmission mechanism including a longitudinally extending shaft, a fast speed gear train, a slow speed gear train, each gear train including a terminal gear coaxial with said longitudinal shaft, and friction clutches one individual to each terminal gear for connecting said gears in driving relation with said shaft, and a reversing mechanism coaxial with each alined shaft.

27. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including alined shafts one connected to each member, a separate and distinct plural speed transmission mecha-

nism for each shaft, each transmission mechanism including a longitudinally extending shaft, a fast speed gear train, and a slow speed gear train, each gear train including a terminal gear coaxial with said longitudinal shaft, and a reversing mechanism coaxial with each alined shaft including reversely rotatable gears coaxial with each alined shaft and friction clutches for selectively connecting said reversing gears to their respective shafts.

28. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including alined shafts one connected to each member and a separate and distinct plural speed transmission mechanism for each shaft, each transmission mechanism including a longitudinally extending shaft, a fast speed gear train, a slow speed gear train, each gear train including a terminal gear coaxial with said longitudinal shaft, and friction clutches one individual to each terminal gear for connecting said gears in driving relation with said shaft, and a reversing mechanism coaxial with each alined shaft including reversely rotatable gears coaxial with each alined shaft and friction clutches for selectively connecting said reversing gears to their respective shafts.

29. In a mining machine feeding mechanism, relatively rotatable feeding members disposed with their axes parallel to a transverse vertical plane and each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, and a slow speed gear train, each gear train including a worm wheel coaxial with said shaft.

30. In a mining machine feeding mechanism, relatively rotatable feeding members disposed with their axes parallel to a transverse vertical plane and each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, a slow

speed gear train, each gear train including a worm wheel coaxial with said shaft, and friction clutches one individual to each terminal gear for connecting said worm wheel in 5 driving relation with said shaft.

31. In a mining machine feeding mechanism, relatively rotatable feeding members disposed with their axes parallel to a transverse vertical plane and each adapted to 10 operate directly with flexible feeding means, and motor operated devices for driving said members either separately or simultaneously in a direction to draw in their respective flexible feeding means at relatively high speed or 15 at relatively low speed including a separate and distinct plural speed transmission mechanism for each member, each transmission mechanism including a longitudinally extending shaft, a fast speed gear train, a slow 20 speed gear train, each gear train including a worm wheel coaxial with said shaft, and worms rotating on parallel axes and meshing with said worm wheels respectively.

32. In a mining machine feeding mechanism, relatively rotatable feed operating members disposed with their axes parallel to a transverse vertical plane and each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, a slow speed gear train, each gear train including a worm wheel coaxial with said 35 shaft, and worms rotating on parallel vertically extending axes and meshing with said worm wheels respectively.

33. In a mining machine feeding mechanism, relatively rotatable feeding members each adapted to cooperate directly with flexible feeding means, and motor operated devices for driving said members either separately or simultaneously in a direction to draw in their respective flexible feeding 45 means at relatively high speed or at relatively low speed including a separate and distinct plural speed transmission mechanism for each member, each transmission mechanism including a longitudinally extending shaft, a fast speed gear train, and a slow speed gear 50 train, each gear train including a terminal gear coaxial with said shaft, and transversely extending shafting driven through said gear trains and operatively connected to said 55 members.

34. In a mining machine feeding mechanism, relatively rotatable feeding members each adapted to cooperate directly with flexible feeding means, and motor operated devices for driving said members either sepa- 60

rately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, and a slow speed gear train, each gear train including a worm wheel coaxial with said shaft, and transversely extending shafting driven through said gear trains and operatively connected to said members. 70

35. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, a slow speed gear train, each gear train including a worm wheel coaxial with said shaft, and friction clutches one individual to each terminal gear for connecting said worm wheel in driving relation with said shaft, and transversely extending shafting driven through said gear trains and operatively connected to said members. 80

36. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, a slow speed gear train, each gear train including a worm wheel coaxial with said shaft, and worms rotating on parallel axes and meshing with said worm wheels respectively, and transversely extending shafting driven through said gear trains and operatively connected to said members. 95 100

37. In a mining machine feeding mechanism, relatively rotatable feed operating members each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, a slow speed gear 110 115 train, each gear train including a terminal gear coaxial with said shaft, and transversely extending shafting driven through said gear trains and operatively connected to said members. 120

125 130

train, each gear train including a worm wheel coaxial with said shaft, and worms rotating on parallel vertically extending axes and meshing with said worm wheels respectively, 5 and transversely extending shafting driven through said gear trains and operatively connected to said members.

In testimony whereof I affix my signature.
MORRIS P. HOLMES.
